Application September 14, 1955, Serial No. 534,299

12 Claims. (Cl. 208—95)

This invention relates to a process for treating petroleum fractions. More particularly, this invention relates to the treatment of naphthas for the manufacture of improved motor fuels or motor fuel components.

Petroleum fractions, such as light and heavy straight run naphthas, treated for the manufacture of modern fuels are complex mixtures of hydrocarbons. A variety of treating processes have been employed to upgrade such fractions, e.g., thermal and catalytic cracking and reforming processes. These treating processes have been employed singly and in combination and are designed to effect the dehydrogenation of naphthenes to aromatics, isomerization of n-paraffins to isoparaffins and dehydrocyclization or aromatization of the paraffins to aromatic hydrocarbons. Because these basic upgrading reactions do not always proceed equally well under the same conditions, single step treating processes employing these basic upgrading reactions have the disadvantage that they are inefficient with respect to the desired conversion of one or more of the components in the feed stock. On the other hand, multi-step treating processes have a disadvantage in that large volumes of feed material are handled in each step with the result that handling and investment costs reduce the economies and commercial attractiveness of such schemes.

In accordance with our invention, we have provided a combination treating process wherein a petroleum fraction is converted into a high octane motor fuel component, and wherein only a portion of the fraction is subjected to multiple treating steps.

A principal object of this invention is to provide an improved process for the treatment of petroleum fractions. A further object is to provide a process for the manufacture of motor fuel components of improved quality. Still another object is to provide a combination treating process for a more efficient conversion of petroleum fractions. How these and other objects are accomplished will become evident from the accompanying detailed description and drawing which schematically illustrates a petroleum processing scheme of the practice of our invention.

In accordance with this invention, there is provided a process for treating a petroleum fraction, such as a heavy straight run naphtha having a boiling point in the range 175—450° F. and containing straight chain and non-straight chain hydrocarbons, which comprises converting said fraction, such as by catalytic reforming, e.g. Platforming, to produce an effluent having improved motor fuel qualities, said effluent containing a substantial proportion of straight chain and non-straight chain hydrocarbons, fractionating said effluent (reformate) to produce a relatively light fraction boiling below about 250° F., e.g. below about 210° F., and a remaining relatively heavy fraction, contacting said light fraction with a solid adsorbent which selectively adsorbs straight chain hydrocarbons to the substantial exclusion of non-straight chain hydrocarbons to adsorb straight chain hydrocarbons from said light fraction and blending the resulting

treated light fraction, now substantially free of straight chain hydrocarbons, with said heavy fraction to produce a petroleum product having improved qualities as a motor fuel.

5 In a preferred embodiment of the invention, the straight chain hydrocarbons adsorbed from the light fraction are desorbed and converted by direct recycle to the catalytic reformer or isomerizer to produce a desorbed-converted product having improved motor fuel qualities. This product from the conversion of straight chain hydrocarbons may be recovered separately, recycled to the adsorption step to further remove straight chain hydrocarbons or it may be blended with the aforementioned blend of said treated light fraction and said heavy fraction.

A petroleum fraction suitable for use in the practice of this invention might have an initial boiling point in the range 50—300° F. and an end point in the range 200—475° F., more or less. Furthermore, a petroleum fraction suitable for use in the practice of this invention must contain both straight chain and non-straight chain hydrocarbons and might have the following composition:

Hydrocarbon Type	Percent by Vol.
Naphthenes.....	0-75
Aromatics.....	0-50
Paraffins (including normal paraffins and iso-paraffins).....	3-90
Unsaturates (including normal olefins and iso-olefins).....	0-50

30 The straight chain hydrocarbons, for example the normal paraffin content of petroleum fractions suitable for use in the practice of this invention, is frequently in the range 3—50% by volume. Typical refinery stocks which are applicable to the practice of this invention are a wide boiling straight run naphtha, a light straight run naphtha, a heavy straight run or a catalytic cracked naphtha, a thermally cracked reformed naphtha. This invention, however, is particularly applicable to the treatment of catalytic reformates in the naphtha boiling range, such as a Platformate, a Hydroformate, an Ultraformate and the like.

35 Any solid adsorbent which selectively adsorbs straight chain hydrocarbons to the substantial exclusion of non-straight chain hydrocarbons can be employed in the practice of this invention. It is preferred, however, to employ as the adsorbent certain natural or synthetic zeolites or alumino-silicates such as a calcium alumino-silicate which exhibit the properties of a molecular sieve, that is, adsorbents made up of porous matter or crystals wherein the pores are of molecular dimension and are of uniform size. A particularly suitable solid adsorbent for the adsorption of straight chain hydrocarbons to the substantial exclusion of non-straight chain hydrocarbons is a calcium alumino-silicate manufactured by Linde Air Products Company and designated Linde Type 5A Molecular Sieve. The crystals of this particular calcium alumino-silicate, apparently actually a sodium calcium alumino-silicate, have a pore size or pore diameter of about 5 Angstrom units, a pore size efficient to admit straight chain hydrocarbons such as the n-paraffins, to the substantial exclusion of the non-straight chain hydrocarbons, such as the naphthenic, aromatic, iso-paraffinic, and iso-olefinic hydrocarbons.

40 Other solid selective adsorbents may be employed in the practice of this invention. For example, it is contemplated that adsorbents having the property of selectively adsorbing straight chain hydrocarbons to the substantial exclusion of non-straight chain hydrocarbons in the manner of a molecular sieve may be obtained by suitable treatment of various oxide gels, especially metal oxide gels of the polyvalent amphoteric metal oxides.

Other suitable selective adsorbents are known and include the synthetic and natural zeolites which, when dehydrated, may be described as crystalline zeolites having a rigid 3 dimensional anionic network having interstitial dimensions sufficiently large to adsorb straight chain hydrocarbons but sufficiently small to exclude the non-straight chain hydrocarbons. The naturally occurring zeolite, chabazite, exhibits such desirable properties. Another suitable naturally occurring zeolite is analcrite $\text{NaAlSi}_2\text{O}_6\text{H}_2$ which, when dehydrated, and when all or part of the sodium is replaced by an alkaline earth metal such as calcium, yields a material which may be represented by the formula $(\text{Ca},\text{Na})\text{Al}_2\text{Si}_4\text{O}_{12}\text{.2H}_2\text{O}$ and which, after suitable conditioning, will adsorb straight chain hydrocarbons to the substantial exclusion of non-straight chain hydrocarbons. Naturally occurring or synthetically prepared phacolite, gmelinite, harmotome and the like or suitable modifications of these products by base exchange are also applicable in the practice of this invention.

Other solid adsorbents which selectively adsorb straight chain hydrocarbons, such as n-paraffins and n-olefins, to the substantial exclusion of the non-straight chain hydrocarbons are known.

Referring now to the drawing which schematically represents one embodiment of the practice of this invention, a petroleum fraction in the gasoline boiling range, such as a heavy straight run naphtha having an initial boiling point in the range 150-250° F. and an end point in the range 350-475° F. and containing straight chain and non-straight chain hydrocarbons, is introduced via line 11 into converter 12. Converter 12 may be a thermal or a catalytic converting unit, preferably a catalytic reforming unit such as a Platformer. The converting unit advantageously employs a platinum-containing reforming catalyst and is operated under reforming conditions to upgrade the petroleum fraction by dehydrogenation, isomerization and/or dehydrocyclization. The resulting upgrading fraction is transferred via lines 13, 14 and 15 into fractionator 16. If, however, it is desired to remove the hydrogen and other fixed gases (methane and ethane) produced in the converting unit prior to introducing the resulting upgraded fraction into fractionator 16, the upgraded fraction is directed via line 13 into a liquid-gas separator 18. In the separator, the hydrogen and other fixed gases are removed overhead via line 19 and are available for recycle via lines 20 and 11 to supply hydrogen to the converting unit. In fractionator 16, the converted feed is separated into an overhead light fraction and a relatively heavy bottoms fraction. The light fraction boils below about 250° F., such as below 210° F., and may amount to as much as 60% by volume of the converted feed from converter 12. The heavy fraction is separately recovered via line 23. It has been found that this relatively heavy fraction is more refractory or less responsive to upgrading, as evidenced by octane number increase, by a subsequent treating process (straight chain hydrocarbon adsorption separation). The light fraction is directed through line 22 to a heater 24. In heater 24, the light fraction is brought up to a suitable temperature in preparation for the separatory adsorption operation for the removal of straight chain hydrocarbons therefrom. The heated light fraction is transferred via line 25 to adsorber 26.

In adsorber 26, the light fraction is contacted with a solid adsorbent, such as an alkaline earth metal aluminosilicate, preferably a calcium alumino-silicate, to effect the adsorptive separation of straight chain hydrocarbons therefrom. Adsorption conditions in the adsorber may range between about 300° to 750° F. and at any suitable pressure between 0-2000 p.s.i.g. It is preferred to maintain the adsorption conditions such that the light fraction undergoing treatment is in the vapor phase. After suitable contact within the adsorber to effect the adsorption of straight chain hydrocarbons, the treated light fraction, 75

now substantially free or at least having a reduced straight chain hydrocarbon content, is recovered via line 29. The resulting improvement in the treated light fraction as a motor fuel is evidenced by an increase in octane number. The thus-treated light fraction is blended via line 30 with the heavy fraction recovered via line 23 to produce an increased yield of high quality, relatively high-octane motor fuel.

On completion of the adsorption operation, the adsorber is subjected to desorption conditions to effect the removal of the adsorbed straight chain hydrocarbons. Suitable desorption conditions include a temperature in the range 500° F. to 1100° F. more or less, and a pressure in the range 0-1000 p.s.i.g. It is preferred to carry out the desorption operation under such conditions that the straight chain hydrocarbons are desorbed or recovered in the vapor phase. Desorption of the straight chain hydrocarbons is facilitated by the introduction of a stripping medium via line 32 to carry the desorbed straight chain hydrocarbons from the adsorption zone. Gases suitable as a stripping medium include hydrogen, nitrogen, carbon monoxide, carbon dioxide, methane, steam, iso-butane, as well as gases containing H_2 and certain normally gaseous hydrocarbons such as methane, ethane and propane removed from the liquid-gas separator 18 via line 19.

The desorbed straight chain hydrocarbons and the accompanying stripping medium are conducted through line 33 into a liquid-gas separator 34. In the separator, the stripping gases are separated and removed via line 38 for recycle to adsorber 26 or to converter 12, or the total desorption effluent without separation may be directly passed to converter 36, particularly if the stripping gas is comprised predominantly of hydrogen. The straight chain hydrocarbons remaining in separator 34 are transferred via line 35 to converter 36. Advantageously, the straight chain hydrocarbons are upgraded in converter 36 by isomerization. The resulting isomerized straight chain hydrocarbons may be recovered via line 42 as a separate product or as an upgraded component suitable for blending with the aforementioned blend of heavy and treated light fractions. The isomerized fraction may also be recycled via line 43 for repassage through the solid adsorbent to effect removal of the remaining straight chain hydrocarbons. By operating in this manner, it is possible to upgrade all of the straight chain hydrocarbons removed from the light fraction thereby producing an additional upgraded fuel component.

If desired, the straight chain hydrocarbons, after desorption, can be recycled directly to converter 12 to effect isomerization and dehydrocyclization. This operation is particularly advantageous when the hydrogen-containing gas from separator 18 is employed as the stripping medium during desorption.

Illustrative of the practice of this invention, a heavy straight run naphtha having a boiling range in the range 175-475° F. is heated and passed to a catalytic reforming unit e.g., Platformer in contact with a platinum-containing catalyst under reforming conditions. Suitable reforming conditions include pressures in the range 150-900 p.s.i.g. and temperatures in the range 750-1000° F., more or less. The effluent or reformate from the Platformer may have a boiling range of from 75° F. to 440° F. and a research octane number clear of about 87. The reformate is conducted to a liquid-gas separator for the removal of hydrogen and fixed gases and the liquid from the separator heated and passed into a fractionator. The fractionator is operated to pass overhead a relatively light fraction boiling below 250° F. and to leave behind a heavy bottoms fraction. The light fraction amounting up to about 60% by volume of the feed stream may have a research octane of about 81 while the heavy fraction may have a research octane number of about 98. The light fraction is contacted with a solid adsorbent such as a sodium calcium alumino-silicate,

e.g. Linde Type 5A Molecular Sieve, at a temperature in the range 425-650° F. to effect adsorption of the straight chain hydrocarbons therefrom. The resulting treated light fraction, now substantially free of straight chain hydrocarbons and having a research octane number substantially about the untreated light fraction, is suitable for blending with the recovered heavy fraction to produce a motor fuel component having a substantially improved octane number.

It is not necessary to remove the straight chain hydrocarbons from the aforementioned heavy bottoms fraction since this fraction already possesses a relatively high octane number and any octane improvement realized by removing the straight chain hydrocarbons therefrom would be slight. This is indicated in the accompanying Table No. I.

TABLE NO. I

Selective finishing of close boiling fractions from a Platformate

[Whole Platformate 87.1 Clear Research Octane No.]

Cut No.	Boiling Range, °F.	Vol. Per- cent Cumula- tive	ASTM Res. Oct. Clear		Octane No. Im- prove- ment
			Un- treated	Treated for removal of straight chain hydro- carbons	
1	75-138	10.6	78.9	89.2	11.3
2	138-171	20.6	71.0	82.2	11.2
3	171-186	30.7	60.6	73.1	12.5
4	186-209	40.7	78.1	91.0	12.9
5	209-225	50.7	82.0	90.0	8.0
6	225-249	60.8	86.6	94.3	7.7
7	249-264	70.8	95.6	99.6	4.0
8	264-311	80.9	97.6	100.9	3.3
9	311-350	86.1	101.1	102.3	1.2
10	350-440	97.9	103.8	104.6	0.8

It will be seen that the response to octane improvement by the removal of straight chain hydrocarbons is best in the low boiling fraction amounting to 30 to 40 volume percent, i.e. the fractions boiling below about 210° F. The octane improvement of these fractions amount to about 12 octane numbers. The fractions boiling between 210° F. and 250° F., show an improvement of about 8 octane numbers while the heavy portion of the fuel shows little response to the adsorption treatment. It is apparent from Table No. I that the adsorption of straight chain hydrocarbons from a reformate or Platformate is highly effective in upgrading a fraction boiling below about 250° F., amounting to about 60% of the whole reformate. In accordance with the practice of this invention, if a greater throughput is desired in the process, only those fractions showing maximum response to selective adsorption, i.e. the fractions boiling below about 210° F., should be treated in the adsorber. In this case, only about 40% of the reformate is subjected to adsorption thereby greatly increasing the throughput of the two stage process of this invention.

This application is a continuation-in-part of our application Serial No. 483,998, filed on January 25, 1955 which, in turn, is identified as a continuation-in-part of our copending application Serial No. 478,426, filed December 29, 1954.

As is evident to those skilled in the art, many modifications, substitutions and changes are possible in the practice of this invention without departing from the spirit or scope thereof.

We claim:

1. A process for treating a petroleum fraction containing straight chain and non-straight chain hydrocarbons which comprises catalytically reforming said fraction to produce an effluent suitable as a motor fuel component, said effluent containing a substantial proportion of straight chain and non-straight chain hydrocarbons,

fractionating said effluent to produce a light fraction boiling below about 250° F. and a heavy fraction, contacting said light fraction with a solid adsorbent which selectively adsorbs straight chain hydrocarbons to the substantial exclusion of non-straight chain hydrocarbons to adsorb straight chain hydrocarbons from said fraction and blending the resulting treated light fraction and said heavy fraction to produce a petroleum fraction having improved qualities as a motor fuel.

5 10. 2. A process according to claim 1 wherein the adsorbent is a calcium alumino-silicate.

3. A process according to claim 1 wherein the adsorbent is a sodium calcium alumino-silicate.

4. A process according to claim 1 wherein the adsorbent is an alkaline earth metal alumino-silicate.

5. A process for the manufacture of a motor fuel component which comprises subjecting a hydrocarbon fraction in the naphtha boiling range to catalytic reforming to produce an effluent having improved properties as a 20 motor fuel component, said effluent containing straight chain and non-straight chain hydrocarbons, fractionating said effluent to produce a light naphtha fraction boiling below about 250° F. and a heavy fraction, contacting said light fraction with a solid adsorbent which selectively adsorbs straight chain hydrocarbons to the substantial exclusion of non-straight chain hydrocarbons to adsorb straight chain hydrocarbons from said light fraction and blending the resulting treated light fraction and said heavy fraction.

30 6. A process for treating a petroleum fraction boiling in the range 75-450° F. which comprises catalytically reforming said fraction in the presence of a platinum-containing catalyst to produce a reformate in the naphtha boiling range, said reformate containing straight chain and non-straight chain hydrocarbons, separating from said reformate a light fraction boiling below about 250° F. and a heavy fraction, contacting said light fraction with a solid adsorbent which selectively adsorbs straight chain hydrocarbons to the substantial exclusion of non-straight chain hydrocarbons to adsorb straight chain hydrocarbons from said light fraction and blending said light fraction, now substantially free of straight chain hydrocarbons with said heavy fraction.

7. A process according to claim 6 wherein the straight chain hydrocarbons are desorbed from the solid adsorbent and recycled to the catalytic reforming operation.

8. A process for treating a petroleum naphtha which comprises catalytically reforming said naphtha to produce an effluent containing hydrogen and a reformate suitable as a motor fuel component, said reformate containing straight chain and non-straight chain hydrocarbons, separating from said effluent a hydrogen-rich gas and fractionating said reformate into a light fraction and a heavy fraction, said light fraction boiling below about 210° F. and containing straight chain and non-straight chain hydrocarbons, contacting said light fraction with a solid adsorbent which selectively adsorbs straight chain hydrocarbons to the substantial exclusion of non-straight chain hydrocarbons to adsorb straight chain hydrocarbons from said light fraction, desorbing said straight chain hydrocarbons from said adsorbent, isomerizing said desorbed straight chain hydrocarbons to produce a mixture containing straight chain and non-straight chain hydrocarbons and blending said mixture with the resulting treated light fraction and said heavy fraction to produce a motor fuel component of improved quality.

9. A process according to claim 8 wherein the hydrogen-rich gas is recycled to the catalytic reforming operation.

10. A process according to claim 8 wherein said hydrogen-rich gas is employed to desorb straight chain hydrocarbons from said adsorbent.

11. A process according to claim 8 wherein said hydrogen-rich gas is employed to desorb the straight chain

hydrocarbons from said adsorbent and wherein the resulting desorbed straight chain hydrocarbons together with hydrogen-rich gas is passed to the isomerization operation.

12. A process for treating a petroleum naphtha which comprises catalytically reforming said naphtha to produce an effluent containing hydrogen and a reformate suitable as a motor fuel component, said reformate containing straight chain and non-straight chain hydrocarbons, separating from said effluent a hydrogen-rich gas and fractionating said reformate into a light fraction and a heavy fraction, said light fraction boiling below about 210° F. and containing straight chain and non-straight chain hydrocarbons, contacting said light fraction with a solid adsorbent which selectively adsorbs straight chain hydrocarbons to the substantial exclusion of non-straight chain hydrocarbons to adsorb straight chain hydrocarbons 10

5

5

bons from said light fraction, desorbing said straight chain hydrocarbons from said adsorbent by contacting

said adsorbent with said hydrogen-rich gas, and passing

the effluent comprising desorbed straight chain hydrocar-

bons and said hydrogen-rich gas resulting from the de-

esorption operation to the aforesaid catalytic reforming

operation.
